UNITED STATES PATENT OFFICE

2,487,937

DENTAL CASTING MACHINE

Anton F. Miskunas, Chicago, Ill.

Application June 17, 1946, Serial No. 677,233

4 Claims. (Cl. 18—5.7)

1

This invention relates to dental casting machines and more particularly to a centrifugal dental casting apparatus, although certain features thereof may be employed to advantage for other purposes. It contemplates more especially the provision of a rotary casting arm type of dental casting machines wherein counter-balancing crucibles are employed at variable distances from the center of rotation depending upon conditions and other operating factors.

In dental laboratories, there is need for various apparatus employing electric motors and it has been found highly desirable to combine dental casting machine instrumentalities with other apparatus such as polishing and grinding equipment for use with a common or single motor. This increases the flexibility of dental laboratory apparatus and materially enhances the use to which apparatus in a dental laboratory may be put.

Dental laboratories are usually small and constitute a comparatively small adjunct to the dental practitioner's office space. This renders it extremely advantageous to provide dual purpose equipment utilizing a single or common motor, such as centrifugal casting instrumentalities and polishing or grinding equipment. These respective instrumentalities have different load and operating characteristics so one should be conveniently and readily detachable from the other through the adjustment of the motor position so that either can be used with utmost efficiency. This, together with other advantages, such as improved casting instrumentalities comprise the teachings of the present invention.

One object of the present invention is to simplify the construction and improve the operation of devices of the character mentioned.

Another object is to provide an improved dental casting machine wherein dual crucibles are used in counter-balanced relation to each other.

Still another object is to provide an improved dental laboratory equipment embodying a power operating dental casting machine as an alternate of other power driven equipment operative with the same motor.

A further object is to provide an improved dental casting machine of centrifugal counter-balanced type embodying dual crucibles to accomplish that end.

A still further object is to provide an improved dental casting apparatus having a power driven motor that is operatively connected or readily disconnected therewith.

Still a further object is to provide a dental

casting machine with a motor that is readily detachable or attachable therewith by adjusting the position thereof in relation to a coupling element.

5 Other objects and advantages will appear from the following description of an illustrative embodiment of the present invention.

In the drawings:

Figure I is a front view in elevation of a device embodying features of the present invention.

Figure II is an end sectional view in elevation taken substantially along line II—II of Figure I.

Figure III is an end sectional view in elevation taken substantially along line III—III of Figure I.

15 Figure IV is a fragmentary perspective view of the gear housing and crucible support shaft showing the counter-balanced relation of the crucibles thereon.

Figure V is a plan sectional view taken substantially along line V—V of Figure I.

20 Figure VI is a fragmentary sectional view in elevation taken substantially along line VI—VI of Figure V.

Figure VII is a fragmentary sectional view of the clutch taken substantially along line VII—VII of Figure I.

Figure VIII is a plan view of the clutch face viewed substantially from line VIII—VIII of Figure VII.

30 The structure selected for illustration is not intended to serve as a limitation upon the scope or teachings of the invention, but is merely illustrative thereof. There may be considerable variations and adaptations of all or part of the teachings depending upon the dictates of commercial practice. The present embodiment comprises a base 10 preferably though not essentially of rectangular configuration for mounting to the top surface of a work bench 11 or the like.

35 The base 10 is provided with upstanding brackets 12—13, in this instance two, which are transversely disposed in parallel spaced relation to provide centrally aligned integral ears 14—15.

The integral ears 14—15 have axially aligned 40 threaded bores 16—17 therethrough to receive a correspondingly threaded elongated rod 18 therethrough for threaded engagement therewith. The threaded rod 18 is journalled to confronting transverse sides 19—20 comprising part of a motor casing mount 21. Collars 22—23 retain the threaded rod 18 against axial displacement relative to the motor casing mount 21, but permit relative rotation therewith to linearly displace the motor casing mount 21 which is slidably supported on the transverse brackets

12-13. A manual rotary displacing hand wheel 24 is fixed to the outer free extremity of the rod 18 to longitudinally displace the motor casing mount 21 in opposite directions on the base 10 as will appear more fully hereinafter.

An electric motor 25 of suitable capacity is fastened through its base flange 26 to the casing mount 21 by means of bolts 27 so that rotation of the hand wheel 24 in either direction will correspondingly displace the motor 25 longitudinally along the base 10. Suitable polishing or grinding instrumentalities such as the wheel 28 are detachably fixed to an outwardly extending armature shaft 29 of the motor 25 so that the latter will be useful for the usual grinding and polishing operations usually found necessary in a dental laboratory. These operations usually require high speeds for which motors 25 are usually designed, and for that reason no other load should be harnessed to the motor 25 during such operations.

In order to provide an additional service for the motor 25, however, a dual service may be provided by utilizing the motor shifting wheel 24 to cause one conventional rubber damping clutch element 30 on the oppositely extending motor armature shaft end 31 to engage another complementary conventional rubber damping clutch element 32 fixed to a stud shaft 33 (Figure VII). The shaft 33 is journaled in an upstanding bearing bracket 34 bolted to the base 10 as at 35 (Figure II). The stud shaft 33 carries a spur gear 36 beyond the bearing bracket 34, and the gear 36 meshes with a pinion 37 fixed to a shaft 38 journaled between the bearing bracket 34 and another upstanding confronting bracket 39. The latter is bolted as at 40 to the base 10 (Figures I and III).

The shaft 38 carries an appreciably larger spur gear 41 in a bell housing 42 having another pinion housing 43 thereon to comprise part of the bearing bracket 39. A pinion 44 is mounted on a driven stud shaft 45 journaled in a pinion housing shaft extension 46 superposed above a bell housing shaft extension 47 which supports the shaft 38. A spur gear 48 is fixed to the other end of the shaft 45 to mesh with the pinion 37 to provide a double gear box involving the shafts 38-45. This imparts a more rugged construction and provides a better balanced starting torque for the load on the driven shaft 45 that has an elongated extension 49 mounted in a tubular shaft housing 50 comprising part of a face plate 51 formed integrally therewith. A bracket web 52 reinforces the tubular housing 50 relative to the bell housing face plate 51 (Figure IV) to rigidly support the shaft tube 50 with the elongated driven shaft 45 journaled therein.

The driven shaft 45 with its extension 49 terminates in a threaded extremity to receive a locking nut 53 to retain spacing collars 54-55 thereon for the reception of a rotary arm 56 which is slotted therethrough as at 57 to receive the shaft extension 49 therethrough. The spaced collars 54-55 frictionally engage both sides of the slotted arm 56 to retain its balanced or unbalanced position on the shaft extension 49 when the nut 53 is drawn tight. With this arrangement, the arm 56 may be positioned off-center to compensate for varying content loads carried in dental crucibles 59-60.

The crucibles 59-60 are adjustably fixed through threaded stud fasteners 61-62 in elongated slots 63-64 provided in the confronting arms 65-66 of arcuate stirrup-type cradles

67-68, respectively. The cradles 67-68 are apertured intermediate their arms 65-66, respectively, to receive threaded stud terminals 69-70 (Figure IV) therethrough to enable the mounting thereof to the extremities of the arm 56. The threaded stud terminals 69-70 comprise, in this instance, integral longitudinal extensions of the dual crucible supporting rotary arm 56, and the cradles 59-60 are retained thereon by fastener nuts 71 and washers 72. With this arrangement, one crucible 59 could be used for cooling while the other crucible 60 is centrifugally casting responsive to the constant rotation of the supporting arm 56. A balanced or counter-balanced rotary dual functioning apparatus is thus produced with uniform operating characteristics.

This dual crucible structural rotary support may also be utilized individually so that the crucibles 59-60 may be alternatively utilized for centrifugal casting and, thereby, allow the other crucible to cool off whether empty or provided with an investment and its content. An empty crucible would also serve to effectively counter-balance, although the off-center adjustment of the rotary arm 56 could be utilized as an accurate balancing control depending upon the respective weights in the crucibles. This coupled with the double gear box involving shafts 38-45, provides a sturdy, balanced and highly flexible casting machine that can be readily detached so that the motor 25 can be utilized to operate the instrumentalities 28 or the latter's counterpart.

While I have illustrated and described a preferred embodiment of this invention, it must be understood that the invention is capable of considerable variation and modification without departing from the spirit of the invention. I, therefore, do not wish to be limited to the precise details of construction set forth, but desire to avail myself of such variations and modifications as come within the scope of the appended claims.

I claim:

1. In a device of the character described, the combination with a base, of an electric motor on said base, a bearing bracket on said base, a driven shaft journaled in said bearing bracket, a train of gears interposed between said driven shaft and said electric motor, an arm having a slotted mid-portion, said arm being adjustably connected to said driven shaft within the limits of said slotted mid-portion to vary the axial position of attachment along said arm, and dental casting crucibles fixed to the extremities of said arm for rotation responsive to the operation of said electric motor.

2. In a device of the character described, the combination with a base, of an electric motor on said base, a bearing bracket on said base, a driven shaft journaled in said bearing bracket, a double train of gears interposed between said driven shaft and said electric motor, an arm having a slotted mid-portion, said arm being adjustably connected to said driven shaft within the limits of said slotted mid-portion to vary the axial position of attachment along said arm, dental casting crucibles fixed to the extremities of said arm for rotation responsive to the operation of said electric motor, and means for shifting said electric motor on said base for operative connection and inoperative disconnection with said driven shaft.

3. In a device of the character described, the combination with a base, of an electric motor on said base, a bearing bracket on said base, a driven shaft journaled in said bearing bracket, a train

of gears interposed between said driven shaft and said electric motor, an arm having a slotted mid-portion, said arm being adjustably connected to said driven shaft within the limits of said slotted mid-portion to vary the axial position of attachment along said arm, dental casting crucibles fixed to the extremities of said arm for rotation responsive to the operation of said electric motor, coupler elements between said electric motor and said train of gears, and means for shifting said electric motor on said base for operative connection and inoperative disconnection of said coupler elements.

4. In a device of the character described, the combination with a base, of an electric motor on said base, a bearing bracket on said base, a driven shaft journaled in said bearing bracket, a train of gears interposed between said driven shaft and said electric motor, an arm having a slotted mid-portion, said arm being adjustably connected to said driven shaft within the limits of said slotted mid-portion to vary the axial position of attachment along said arm, dental casting crucibles fixed to the extremities of said arm for rotation responsive to the operation of said electric motor, 25

coupler elements between said electric motor and said train of gears, and screw means for shifting said electric motor on said base for operative connection and inoperative disconnection of said coupler elements, said electric motor having an armature shaft for receiving high speed polishing and grinding wheels thereon for operation when said coupler elements are disconnected.
